DESIGN FOR A TEXTILE FABRIC

Kurt Lehmann, New York, N. Y., assignor to Emanuel Roth Co. Inc., New York, N. Y., a corporation of New York

Application December 7, 1938, Serial No. 81,619

Term of patent 3½ years

To whom it may concern:

Be it known that I, Kurt Lehmann, a citizen of the United States, residing at New York, in the county and State of New York, have invented
a new, original, and ornamental Design for a Textile Fabric, of which the following is a specification, reference being had to the accompanying drawing, forming part thereof, wherein—

The figure is a plan view of a textile fabric showing my new design, with a unit of design outlined in dot and dash lines.

I claim:

The ornamental design for a textile fabric,
substantially as shown and described.
